ABSTRACT OF THE DISCLOSURE

A stocking double welt having registering portions thereof knit of conventional plain loops under normal tension and other registering portions knit of high stretch yarn under increased tension to permit adequate stretching and adequate recovery.

My invention relates to a stocking and it relates more particularly to improvements in the construction of the welt.

One object of the invention is to provide an improved stocking.

A further object is to produce a welt construction wherein the welt stretches longitudinally and radially, and wherein the stretchability and the ability to recover from the stretched state, are greatly increased.

A still further object is to produce an improved stocking which includes a runguard area intermediate the welt and the top of the leg.

A still further object is to produce a stocking which has no after welt but which presents the appearance of having one.

These and other objects are attained by my invention as set forth in the following specification and as shown on the accompanying drawings in which:

FIG. 1 is a highly diagrammatic side elevational view of a stocking embodying the invention.

FIG. 2 is a highly diagrammatic sectional view of the same.

FIG. 3 is a highly diagrammatic side elevational view of the upper portion of the welt showing a slightly modified construction.

In the drawing, 10 designates a stocking having a welt 12, a leg 14, a heel 16, a foot 18, and a toe 20. The leg, heel, foot and toe form no part of this invention, and therefore their structure is not shown nor described.

The welt shown in FIGS. 1 and 2 is formed of an inner ply 22 and an outer ply 24, with the free edge of outer ply 24 knitted in with the inner ply as at 26, in the usual way.

To carry out my invention, I knit an area 28 of the inner ply and a registering area 30 of the outer ply, of a highly stretchable yarn. By this term I mean a yarn which is treated so as to be several times more stretchable than a yarn of the same material and denier which has not been so treated. Such yarns are available under various generic names such as torque, spandex and so on, and under the trademark "Helanca."

The portions of the inner and outer plies 22 and 24 above line 32 are knit in any desired manner and under normal tension. But, selected areas 28 and 30 are knit of plain stitches but under a slightly increased tension

2

to form loops which are tighter than those of which the balance of the welt is formed.

The highly stretchable yarn permits bidirectional stretching of the fabric of areas 28 and 30 and the tight loop formation insures complete recovery from the stretched state.

Areas 28 and 30 are preferably knit so as to present an attractive simulation of an after welt.

Below areas 28 and 30 I knit a narrow band 34 of lace, or non-run stitch, to prevent any run developing in the welt from extending into the leg.

While in the preferred embodiment I place areas 28 and 30 in the lower portion of the welt, it is within the scope of this invention to place the high-stretch-high recovery areas at the top of the welt, as shown in FIG. 3, or elsewhere in the body of the welt.

A stocking welt constructed as shown in FIG. 1, will, after repeated washings, provide ample stretch at the knee when the leg is bent, and by completely recovering it maintains a tight, smooth appearance, instead of the wrinkled, baggy appearance which conventionally knit stockings develop.

Ample stretching is essential to permit comfortable walking and squatting, or bending, in which posture the leg is doubled up, and it is essential to the durability of the stocking.

When placed at the top of the welt or at some intermediate position, areas 28 and 30 provide for ample stretching and their large recovering capacity serves as a support and helps uphold the hose on the leg.

Since, except as pointed out, the structure of FIG. 3 is the same as that of FIG. 1, the parts of FIG. 3 have been designated with the prime of the numbers used in FIG. 1.

What I claim is:

1. A stocking welt comprising an inner ply and an outer ply transversely registering areas of which are knit of plain loops and under tension of a first value, other transversely registering areas of said plies being knit of plain loops of high stretch yarn and under tension of a second value greater than said first value, and a runguard connecting said welt to the upper end of the leg of the stocking.
2. The stocking defined in claim 1 wherein said registering portions are disposed immediately above the lower end of said welt.
